UNITED STATES PATENT OFFICE.

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Application filed October 29, 1926. Serial No. 144,935.

My invention relates to railway signaling, myself to this particular form or location of signals. 55
and is particularly adapted for, though in no way limited to, the control of signals located adjacent passing sidings between stretches of track over which traffic moves in both directions.

I will describe one form of apparatus embodying my invention and will then point out the novel features thereof in claims.

10 In the accompanying drawings, Fig. 1 is a diagrammatic view showing a stretch of single track with passing sidings and a plurality of signals for governing traffic through the stretch in both directions. Figs. 2 and 15 3 are views which when placed end to end with Fig. 2 on the left constitute a diagrammatic view illustrating one form and arrangement of circuits for controlling certain of the signals shown in Fig. 1 in accordance 20 with my invention.

Similar reference characters refer to similar parts in each of the views.

Referring first to Fig. 1, A—H is a stretch of single track between two passing sidings 25 M and O over which traffic moves in both directions. Located at an intermediate point in the stretch is another passing siding N by means of which the stretch A—H is divided into two blocks A—D and E—H extending respectively from the siding M to the siding N and from siding N to siding O. Each of the blocks is divided by insulated joints into several successive sections. For example, block A—D is divided into 30 sections A—B, B—C and C—D, and block E—H is divided into sections E—F, F—G and G—H. Eastbound traffic through the stretch of track shown in the drawing is governed by a plurality of trackway signals 2, 4, 6, 8, 10, 12, 14 and 16, and westbound traffic through this stretch is governed by similar signals 1, 3, 5, 7, 9, 11, 13 and 15. Signals 7 and 8 govern the entrance into the passing siding N from east and west, 40 respectively. In similar manner signal 15 governs the entrance of westbound traffic into siding M and signal 16 governs entrance of eastbound traffic into siding O. As here shown a pair of opposing signals is 45 located adjacent each end of each section and each of the signals is of the three-position semaphore type, each capable of indicating proceed, caution or stop, respectively. It is understood, however, that I do not limit 50

The signals for block A—D are so controlled that when a train moving toward the east enters this block, signals 9, 11 and 13 are placed at stop and signal 9 is held at stop until the train passes out of the block, thus prohibiting a westbound train from entering the block while the east train is anywhere in the block. As the eastbound train enters the block it also causes signal 2 to indicate stop and as it passes signals 4 and 6, these signals are successively caused to change to the stop indication. When the entire train passes out of section A—B, signal 2 changes to the caution indication and when the entire train passes out of section B—C this signal returns to the full proceed indication. Signal 4 changes to caution when the train leaves section B—C and to proceed when the train leaves section C—D. Two or more trains may therefore follow each other through the stretch under the same signal protection as is customarily provided on double track roads. Similarly, when a westbound train enters block A—D signals 2, 4, 6 and 9 are 55 placed at stop and signal 9 subsequently changes successively to caution and proceed as the train proceeds through the block. Signal 11 changes to stop when it is passed by the train and subsequently changes to caution and proceed successively. The signals for block E—H are controlled in the same manner as for block A—D. Furthermore, whenever signal 9 indicates stop, signal 7 indicates caution and whenever signal 7 indicates stop, signal 5 indicates caution. Similarly, whenever signal 10 indicates stop, signal 8 indicates caution, and whenever signal 8 indicates stop signal 6 indicates caution. The control of the signals thus far 60 described is in accordance with standard practice and will be understood without further explanation. 85

It is desirable, however, that when an eastbound train occupies block A—D, signal 5, as well as signal 7, should indicate caution, but that when a westbound train has proceeded some distance beyond signal 9, thus allowing signal 7 to return to caution, as will appear hereinafter, signal 5 should return 90 to the full proceed position.

The reason for this is as follows: Let it be assumed that the signal 5 indicates pro-

- 2
- ceed while signal 9 is at stop, and that two trains moving in opposite directions are approaching siding N. If the eastbound train should pass the point at which signal 5 returns to caution just after the westbound train has passed signal 5 at proceed, the westbound train would receive a stop indication at signal 7 without having been previously warned by a caution indication at signal 5. 10 However, if two westbound trains are moving along the track from H toward A, it is desirable that signal 5 should change to the proceed indication as soon as signal 7 has changed to the caution indication behind the 15 first train, in order to avoid any unnecessary delay to the second train by a caution indication at signal 5.

The object of the present invention is the provision of novel and improved means for 20 accomplishing the desired control of signal 5.

Referring now to Figs. 2 and 3, it will be seen that track sections C—D, D—E and E—F are each provided with a source of 25 track circuit current here shown as a track transformer designated by the reference character T with an exponent corresponding to the location. The secondary 17 of each track transformer T is constantly connected across the rails adjacent one end of the associated section through the usual impedance 19. The primary 18 of each track transformer T is constantly supplied with alternating current from secondary 21 of 30 an adjacent line transformer designated by the reference character L with a suitable exponent and having its primary 20 supplied with alternating current from alternator X over line wires 22. Sections C—D 35 and E—F are each provided with two track relays designated by the reference characters R with suitable distinguishing exponents connected across the rails adjacent the two ends of the section. A single track relay R^s is connected across the rails adjacent the left-hand end of section D—E.

In accordance with the usual practice, each signal is controlled by a line relay designated by the reference character J with a 50 suitable exponent and each signal shown except signals 7 and 8 is also controlled by a repeater relay designated by the reference character P with an appropriate distinguishing exponent. The circuits for certain 55 of the line relays J and repeater relays P are omitted from the drawing for the sake of simplicity, these circuits being so well known in the art as to require no detailed description in this application. For example, relay J⁷ is normally energized but is de-energized when a train occupies section D—E or when relay R^s is de-energized. Relay J⁸, in similar manner, is normally energized, but is de-energized when a train 60 occupies section D—E or when relay R¹⁰ is

is de-energized. Repeater relay P⁹ is normally energized but is arranged to be de-energized when a westbound train occupies section C—D or when an eastbound train occupies any of that portion of track between signals 8 and 2. In similar manner relay P¹⁰ is normally energized but is arranged to be de-energized when an eastbound train occupies section E—F or when a westbound train occupies any portion of 70 the stretch between signals 7 and 1. Relays S¹¹ and S⁵ are two of the usual directional stick relays controlled in accordance with standard practice in absolute permissive block signaling systems. That is, relay S⁵ is normally de-energized but this relay picks up when an eastbound train enters section F—G and the relay is subsequently maintained in its energized condition as long as any portion of this train occupies section F—G. Similarly, relay S¹¹ is normally de-energized but is energized when a westbound train occupies section B—C. 85

Section D—E is also provided with two auxiliary relays Q^s and Q⁷. Relay Q⁷ is 90 normally energized by current from transformer L^P, over a circuit which may be traced from secondary 21 of transformer L^P, through wires 23, 24 and 33, front contact 34 of repeater relay P⁹, wires 35 and 30, winding of relay Q⁷, and common wires 32 back to secondary 21 of transformer L^P. This circuit is closed only when relay P⁹ is energized; but when relay R^s is de-energized, as by the entrance of a train into section D—E, a second circuit is closed for relay Q⁷ and current then flows from secondary 21 of transformer L^P, through wires 23, 24, 25, 26 and 27, back contact 28 of relay R^s, wires 29 and 30, winding of relay Q⁷ and common wire 32, back to secondary 21 of transformer L^P. 95

Relay Q^s is provided with a circuit from secondary 21 of transformer L^E, through wires 79, 80, and 81, front contact 82 of repeater relay P¹⁰, wires 83 and 84, winding of relay Q^s and common wire 32, back to secondary 21 of transformer L^E. A second circuit for relay Q^s passes from secondary 21 of transformer L^P, through wires 23, 24, 25, 26, 36 and 87, back contact 88 of relay R^s, wires 86 and 84, winding of relay Q^s and common wire 32 back to secondary 21 of transformer L^P. It follows that when section D—E is occupied, relays Q^s and Q⁷ are both energized, but that when this section is unoccupied, relay Q^s is energized only when repeater relay P¹⁰ is picked up, and relay Q⁷ is energized only when repeater relay P⁹ is picked up. Stick relay S⁷ is provided with a pick-up circuit which may be traced from secondary 21 of transformer L^P, through wires 23, 24, 25, 26, 36 and 37, back contact 38 of relay R⁹, wire 39, front contact 40 of relay R¹⁰, wire 41, 100 105 110 115 120 125 130

back contact 42 of relay J^7 , wires 43 and 44, front contact 45 of relay Q^7 , wires 46 and 47, winding of relay S^7 and common wire 32 back to secondary 21 of transformer L^P . The circuit just traced is provided with a branch comprising a stick circuit for relay S^7 passing from wire 43, through wire 48, front contact 49 of relay R^{10} , wire 50, front contact 51 of relay S^7 , wires 52 and 47, 10 winding of relay S^7 , and back to common wire 32. It follows that when relay S^7 is energized to close the circuit through the branch just traced, relay Q^7 is eliminated from the control of relay S^7 if relay R^{10} is 15 energized.

Relays Q^7 , J^7 and S^7 control the polarity of the current supplied to line relay J^5 from transformer K^E . Primary 55 of this transformer is constantly supplied with 20 alternating current from secondary 21 of transformer L^E . Under normal conditions relay S^7 is de-energized and relays J^7 and Q^7 are energized as has already been explained. When the relays occupy these positions, current flows from the left-hand terminal of secondary 56 of transformer K^E , through wire 57, front contact 58 of line relay J^7 , wires 59 and 60, front contact 61 25 of auxiliary relay Q^7 , wire 62, back contact 63 of relay S^7 , wire 64, front contact 65 of relay R^5 , wire 66, winding 54 of relay J^5 , wires 67, 68, 69 and 70 and back to the mid-point of secondary 56 of transformer K^E . A second winding 53 on relay J^5 is constantly 30 supplied with alternating current from secondary 21 of transformer L^E , and when winding 54 is energized over the circuit just traced, relay J^5 is energized in the normal direction so that contacts 78 and 75 are 35 swung to the left. When relay S^7 is energized it closes front contact 63 and wire 59 is connected through wire 71 and contact 63 with wire 64 so that current is supplied to energize relay J^5 in the normal direction 40 if relay J^7 is energized irrespective of the condition of relay Q^7 . When relay J^7 is de-energized, when relay Q^7 is energized and when relay S^7 is de-energized, current flows from the right-hand terminal of secondary 56 of transformer K^E , through wires 72 and 73, back contact 58 of relay J^7 , wires 59 and 60, front contact 61 of relay Q^7 , wire 62, back contact 63 of relay S^7 , wire 64, front contact 65 of relay R^5 , wire 66, winding 54 of relay J^5 and wires 67, 68, 69 and 70, back to the mid-point of secondary 56 of transformer K^E . When this circuit is closed the polarity of the current supplied to winding 54 of relay J^5 is such that the relay is energized in the reverse direction, swinging contacts 78 and 75 to their right-hand or reverse positions. If relay J^7 is de-energized so that the right-hand terminal of secondary 56 of transformer K^E is connected with wire 59, and relay S^7 is energized with wire 64, winding 54 of relay J^5 is de-energized.

gized, it will be seen that relay Q^7 is eliminated from the control of relay J^5 and the latter relay will then be energized in the reverse direction irrespective of the condition of relay Q^7 . When relays Q^7 and S^7 are both de-energized, relay J^5 is energized in the reverse direction, the circuit for winding 54 of this relay being from the right-hand terminal of secondary 56 of transformer K^E , through wires 72 and 74, back contact 61 of relay Q^7 , wire 62, back contact 63 of relay S^7 , wire 64, and then through the same path as before to the mid-point of secondary 56. When relay R^5 is de-energized, the circuit for winding 54 of relay J^5 is interrupted and relay J^5 is then de-energized so that the contacts 78 and 75 occupy an intermediate position.

When relay J^5 is energized in either direction and when the stick relay S^5 is de-energized, current flows from secondary 21 of transformer L^E to relay P^5 over a back contact 76 of relay S^5 , and a normal or reverse point of contact 75 of relay J^5 , thereby energizing relay P^5 . Relays J^5 and P^5 control signal 5 so that when relay J^5 is energized in the normal direction and relay P^5 is energized, the proceed circuit for signal 5 is closed. When relay J^5 is energized in the reverse direction and when relay P^5 is also energized the caution circuit is closed for signal 5. When relay P^5 is de-energized, both circuits for signal 5 are interrupted and the signal indicates stop.

Signal 6 for controlling eastbound traffic is controlled by relays J^6 and P^6 in the same manner as just described in connection with the control of signal 5 by relays J^5 and P^5 . Furthermore, the control of relay J^6 by relays J^8 , Q^8 , S^8 and R^6 is similar to the control of relay J^5 by relays J^7 , Q^7 , S^7 , and R^5 and will be readily understood from the drawing without tracing the circuits in detail.

In explaining the operation of the apparatus as a whole, I will first assume that a westbound train traverses the stretch of track shown in the drawing. When the train passes signal 1, this signal goes to stop and signals 10, 12 and 14 also are caused to display stop indications. Signal 8 indicates caution. When the train passes the head-block signal 1, it de-energizes all opposing line relays J and repeater relays P for the block E-H and repeater relay P^{10} is also de-energized. Relay R^8 is energized so that one circuit for relay Q^8 is open at back contact 88 of relay R^8 . The other circuit for relay Q^8 is open at front contact 82 of relay P^{10} so that the entrance of the train into block E-H causes relay Q^8 to become de-energized. Relay S^8 is de-energized however, and relay J^8 is energized, so that current supplied to relay J^6 over back contact 91 of relay S^8 and back contact 92 of relay Q^8 energizes relay J^6 in the reverse direction.

direction. Signal 6 therefore indicates caution and it will therefore be plain that when a westbound train in block E-H is approaching point E, signal 10 indicates stop and signals 6 and 8 both indicate caution.

When the westbound train enters section E-F, relay R⁵ becomes de-energized. The opening of front contact 65 of this relay interrupts the circuit for relay J⁵, and the opening of relay J⁵ in turn de-energizes relay P⁵. With back contact 77 of relay P⁵ open, both operating circuits for signal 5 are interrupted and this signal indicates stop. As the train proceeds in section E-F to a point 15 some distance from signal 7, track relay R¹⁰ becomes de-energized and relay J⁸ then opens, but this has no effect upon relay J⁶ because energy is supplied to relay J⁶ from transformer K^D over back contact 92 20 of relay Q⁸ and back contact 91 of relay S⁸. With the train in section E-F then, signal 6 continues to display a caution indication.

When the train enters section D-E, relay R⁸ becomes de-energized, thereby de-energizing relay J⁷ and causing signal 7 to indicate stop. The closing of back contact 88 of relay R⁸ completes a circuit for relay Q⁸ so that this relay becomes energized and current is then supplied over back contact 93 30 of relay J⁸, front contact 92 of relay Q⁸, and back contact 91 of relay S⁸ to relay J⁶. The polarity of the current thus supplied to relay J⁶ is such that the relay continues 35 to be energized in its reverse direction and signal 6 still indicates caution. Relay J⁷ is de-energized but relay S⁷ remains in its de-energized condition, its pick-up circuit being open at back contact 38 of relay R⁹.

When the train leaves section E-F, relays R¹⁰ and R⁵ pick up, and relay P¹⁰ also picks up. The closing of relay P¹⁰ has no effect upon the apparatus because relay Q⁸, controlled by front contact 82 of relay P¹⁰, is 40 already energized. The closing of front contact 65 of relay R⁵ however, completes a circuit for relay J⁵ including back contact 63 of relay S⁷, front contact 61 of relay Q⁷ and back contact 58 of relay J⁷. Relay J⁵ therefore becomes energized in the reverse 45 direction, closing the circuit for relay P⁵ and energizing that relay. Signal 5 then indicates caution.

When the train enters section C-D, relays R⁶, R⁹ and P⁹ open. The opening of front contact 95 of relay R⁶ interrupts the circuit for relay J⁶ and causes this relay, and hence relay P⁶, to become de-energized. Signal 6 therefore indicates stop. The closing of 50 back contact 38 of relay R⁹ completes a pick-up circuit for relay S⁷ and this relay closes its front contacts. The front contacts 55 of relay S⁷ being closed, relay Q⁷ is eliminated from the control of relay J⁵ which

relay controls signal 5. But with a train 65 moving from section D-E into section C-D, relay J⁷ is de-energized so that relay J⁵ continues to be energized in the reverse direction and signal 5 continues to indicate caution. When the train leaves section 70 D-E, the consequent energization of relay R⁸ opens the circuit for relay Q⁷ and permits this relay to open its front contacts, one circuit for relay Q⁷ being open at front contact 34 of relay P⁹ and the other circuit for this relay being open at back contact 28 of relay R⁸. The opening of front contact 45 of relay Q⁷ interrupts the pick-up circuit for relay S⁷, but the relay is maintained in its energized condition during the 75 operation of relay Q⁷ by current which flows over front contact 49 of relay R¹⁰ and front contact 51 of relay S⁷. This branch circuit therefore operates to hold the relay closed during the brief interval between the opening of front contact 45 of relay Q⁷ and the closing of back contact 45 of that relay. When relay Q⁷ has attained its full de-energized position a retaining circuit for relay 80 S⁷ is closed over back contacts 45 of relay Q⁷, front contact 49 of relay R¹⁰, and front contact 51 of relay S⁷. Relay S⁷ is therefore maintained in its energized condition as long as relay R¹⁰ is energized and relay Q⁷ is de-energized. Relay J⁷ remains de-energized as long as relay R⁹ is open, and relay J⁵ therefore continues to be energized 85 in its reverse direction. Signal 5 therefore still indicates caution.

When the rear end of the train passes some 90 point in section C-D west of signal 9, relays R⁹ and J⁷ pick up, and since relay S⁷ is now energized, relay J⁵ becomes energized in the normal direction to cause signal 5 to indicate proceed. When the train has 95 entirely passed signal 11, signal 7 also indicates proceed.

I have described in detail the operation 100 of the apparatus only for westbound traffic but it should be pointed out that the operation of the apparatus for eastbound traffic is in all respects similar to the operation described and can be readily understood from an inspection of the drawings without tracing the operation in detail.

One feature of my invention is the novel 110 and improved circuits for controlling the stick relays S⁷ and S⁸. It will be plain that relay S⁷, for example, is normally de-energized and that this relay is energized only when a westbound train passes point D. Relay S⁷ when energized, removes relay Q⁷ from the control of relay J⁵ in accordance with usual practice. The novelty of 120 my invention resides in the control of the stick relays S⁷ and S⁸ and in the control of the auxiliary relays Q⁷ and Q⁸ so that signals 5 and 6 are controlled to accomplish 125

double caution indication as required in standard absolute permissive block signaling systems.

Although I have herein shown and described only one form of railway signaling apparatus embodying my invention, it is understood that various changes and modifications may be made therein within the scope of the appended claims without departing from the spirit and scope of my invention.

Having thus described my invention, what I claim is:

1. In combination, a stretch of railway track comprising a first, a second, and a third section, a normally energized line relay arranged to be de-energized when a train occupies said first or second sections, an auxiliary relay arranged to be energized when the second section is occupied but to be de-energized when the first section is occupied, a signal for governing traffic through the third section and controlled by said line relay and by said auxiliary relay, a stick relay arranged when energized to remove said auxiliary relay from the control of the signal, and means for energizing the stick relay when a train moves from the second section into the first section.
2. In combination, a stretch of railway track comprising a first, a second, and a third section, a line relay and an auxiliary relay separately controlled by traffic conditions in the first and second sections, a signal for governing traffic through the third section and controlled by said line relay and by said auxiliary relay, a stick relay arranged when energized to remove the auxiliary relay from the control of said signal, and means for energizing the stick relay when a train moves from the second section into the first section.
3. In combination, a stretch of railway track comprising a first, a second, and a third section, a first and a second track relay for the first and second sections, respectively, a repeater relay controlled by a front contact of the first track relay, a line relay controlled by front contacts of said first and second track relays in series, an auxiliary relay controlled by a front contact of the repeater relay and a back contact of the second track relay in parallel, a signal for the third section controlled by said line relay and by said auxiliary relay, a stick relay arranged when energized to remove the auxiliary relay from the control of the signal, and means for energizing the stick relay when a train moves from the second section into the first section.
4. In combination, a stretch of railway track comprising a first, a second, and a third section, a stick relay, a signal for the third section controlled by said stick relay, and means for energizing the stick relay when a train moves from the second section into the first section.
5. In combination, a stretch of railway track comprising a first, a second, and a third section, a signal for governing traffic in one direction through the third section, a stick relay for controlling the signal, and means effective when a train moving in such one direction enters the first section to energize the stick relay.
6. In combination, a stretch of railway track comprising a first, a second, and a third section, a first, a second, and a third track relay for said first, second and third section, respectively, a line relay having a circuit including front contacts on the first and second track relays, an auxiliary relay provided with a circuit including a back contact of the second track relay; a stick relay having a pick-up circuit including a back contact of the first track relay, a front contact of the third track relay, a back contact of the line relay and a front contact of the auxiliary relay; a branch for said circuit around the said contact on the auxiliary relay and including a front contact of the third track relay and a front contact of the stick relay; and a signal for the third section controlled by the stick relay.

In testimony whereof I affix my signature.
LESTER E. SPRAY.
